US0D1071385S

(12) **United States Design Patent** (10) **Patent No.:** **US D1,071,385 S**
(45) **Date of Patent:** **** Apr. 15, 2025**

(54) **FIRE EXTINGUISHER**

(71) Applicant: **Benxu Automotive Parts (Ningbo) Co., Ltd.**, Zhejiang (CN)

(72) Inventor: **Xuguang Dai**, Zhejiang (CN)

(73) Assignee: **Benxu Automotive Parts (Ningbo) Co., Ltd.**, Zhejiang (CN)

(**) Term: **15 Years**

(21) Appl. No.: **29/958,666**

(22) Filed: **Aug. 21, 2024**

(30) **Foreign Application Priority Data**

Aug. 8, 2024 (EM) 015068997-0001

(57) **CLAIM**

The ornamental design for a fire extinguisher as shown and described.

DESCRIPTION

FIG. 1 is a front, right and top perspective view of a fire extinguisher, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the fire extinguisher that form no part of the claimed design.

1 Claim, 8 Drawing Sheets
